US Patent and Trademark Office; Office Action for U.S. Appl. No. 13/647,319 dated Sep. 5, 2014.

Primary Examiner — Barbara Fox*Assistant Examiner* — Katie S Mroczka(74) *Attorney, Agent, or Firm* — Parsons Behle & Latimer(57) **CLAIM**

The ornamental design for a twisted potato piece, as shown.

DESCRIPTION

This application claims the benefit of U.S. patent application Ser. No. 14/868,987, filed on Sep. 29, 2015, entitled “System for Cutting Spiral Shaped Pieces” the contents of all of which are incorporated herein by reference in their entireties.

FIG. 1 is a perspective view a twisted potato piece;
 FIG. 2 is a front elevational view thereof;
 FIG. 3 is a rear elevational view thereof;
 FIG. 4 is a top plan view thereof;
 FIG. 5 is a bottom plan view thereof;
 FIG. 6 is a right side elevational view thereof; and,
 FIG. 7 is a left side elevational view thereof.
